UNITED STATES PATENT OFFICE.

HENRY WALLNER AND JOSEPH WALLNER, OF NEW YORK, N. Y.

MILITARY CAP.

SPECIFICATION forming part of Letters Patent No. 576,294, dated February 2, 1897.

Application filed November 19, 1896. Serial No. 612,689. (No model.)

To all whom it may concern:

Be it known that we, HENRY WALLNER and JOSEPH WALLNER, citizens of the Empire of Austria-Hungary, residing in the city, county, 5 and State of New York, have invented certain new and useful Improvements in Military Caps, of which the following is a specification.

This invention relates to certain improvements in caps, especially military caps worn 10 by army and navy officers, conductors, police officers, firemen, &c., in which an ear-protector is arranged in connection with the body of the cap in such a manner that it can be placed over the ears whenever desired or stored 15 away in the body of the cap out of sight when not required for use.

In the accompanying drawings, Figures 1 and 2 represent side elevations of our improved military cap, showing the ear-protector 20 respectively as folded away in the body of the cap and as placed in position over the ears. Fig. 3 is an under side view of the cap, showing the spring-actuated sweat-band moved away from the rear part of the cap so as to 25 permit the outward folding of the ear-protector, and Figs. 4 and 5 are respectively a vertical longitudinal section on line 4 4, Fig. 3, and a vertical transverse section on line 5 5, Fig. 3, of our improved military cap, showing 30 the ear-protector folded into the same and the elastic chin-strap likewise stored away in the same.

Similar letters of reference indicate corresponding parts.

Referring to the drawings, A represents the body of a military cap, such as is worn by military officers, conductors, firemen, police officers, &c. The body of the cap is cylindrical in shape and provided with a straight vizor 35 extending forward from the body. To the inside of the body A is applied a sweat-band B, which is attached to the body at its smaller front portion, while its rear portion is not attached to the body of the cap, but provided 40 with two or more flat band-springs b, preferably of thin whalebone or similar elastic but non-corrosive material, by which the rear portion of the sweat-band is always held in position in the body of the cap, except when 45

moved in forward direction, as shown in Fig. 50. To the lower edge of the rear part of the body A is attached an ear-protector C, that is folded into the body of the cap and held in position by the spring-actuated rear portion of the sweat-band B. The ear-protector C is 55 preferably made of cloth of the same color as the body of the cap and provided at its lower front corners with two sections, forming an attached elastic chin-strap D, having a suitable fastening d at the ends when it is desired to hold the ear-protector in position over the ears, as shown in Fig. 2. The elastic chin-strap can be stored away in the body of the cap by placing its sections in loops e, arranged, preferably, in the front part of the 65 cap, so as to be out of the way of the ear-protector stored in the rear part of the cap.

For ordinary use the ear-protector C is stored away in the rear portion of the cap and held in position by the spring-actuated rear 70 portion of the sweat-band, which presses evenly over the same. In cold or stormy weather when it is desired to protect the ears, the spring-actuated rear portion of the sweat-band is moved toward the front portion to 75 clear the ear-protector C, so that the latter can be moved in downward direction over the ears and the rear part of the head, in which position it is retained by connecting the ends of the sections of the chin-strap, so that the 80 ears are fully protected against cold or moisture.

By our improved cap persons in official positions who have to wear military caps for denoting their position or rank can readily protect their ears against cold or storm whenever required by simply placing the ear-protector over the ears, while at other times, when the ear-protector is not required, the same is stored away in the cap without disclosing its 85 presence, as it is firmly held in position in the cap-body by the spring-actuated sweat-band. 90

Having thus described our invention, we claim as new and desire to secure by Letters Patent—

A cap provided with an ear-protector attached to the rear of the cap-body and adapted to fold therein, a sweat-band secured to

the front of said body and free to spring away from the rear thereof, and a band-spring secured to the rear portion of said sweat-band and operating to hold said band in vertical position and to firmly clamp said ear-protector against the body of the cap when folded therein.

5 In testimony that we claim the foregoing as

our invention we have signed our names in presence of two subscribing witnesses.

HENRY WALLNER.
JOSEPH WALLNER.
